TYPEWRITING MACHINE

Filed Jan. 4, 1928

UNITED STATES PATENT OFFICE

CARL E. NORIN, OF JERSEY CITY, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed January 4, 1928. Serial No. 244,398.

This invention relates to fractional line-spacing or part-spacing mechanism for typewriting machines.

The object is to produce an improved mechanism, readily applicable to standard machines, for allowing the operator to rotate the platen through a fraction of a regular line-space forwardly or rearwardly for convenient subscript and exponent writing.

10 A usual line-spacing mechanism substantially includes a ratchet or line-space wheel mounted for rotation with the platen-shaft, and a pivoted spring-pressed detent-arm carrying a detent or pressure roller to cooperate with the notches of said ratchet-wheel for ordinary line-spacing of the platen.

According to a feature of the invention, a hand-operated lever or bell-crank (mounted upon the platen-frame) controls the pivot of 20 the detent-arm, so as to bodily move the same together with the ratchet-wheel in either direction from normal writing position for a fraction of a line-space. The bell-crank is retained in normal position by suitable 25 means, while stops, preferably adjustable, are provided to accurately limit the throw of the bell-crank in each direction from normal position.

Another feature resides in means to urge 30 said operating lever against said adjustable stops when the lever is operated for part-spacing.

A feature of the invention provides independent auxiliary means effective to positively 35 and quickly return the platen from part-spacing to normal writing position. To this end, a hand-operated lever may be pivoted upon the platen-frame, and is formed with a V-shaped or notch-like cam-face to co-operate 40 with a cam-pin or cam-roller provided upon the bell-crank. The lever is normally spring-held out of function, a convenient arrangement being such that depression of the lever, at will, by means of a finger-piece, urges the 45 roller into the apex of the V-shape, which apex determines normal writing position of the platen and excludes the danger of overrunning the same.

As shown on the drawing, the controllable 50 detent is mounted upon a protecting shield-

plate to form a unit, which makes for convenient attachment and liberal adjustment upon a standard Underwood platen-frame.

Other features and advantages will herein-after appear.

In the accompanying drawings,

Figure 1 is a view of the left-hand side of an Underwood platen-frame with the shield-plate carrying the part-spacing mechanism attached thereto, parts being broken away to 60 more clearly show the mechanism which is set for neutral, i. e., for normal writing position.

Figure 2 is a view of the inner face of the shield-plate, showing the part-spacing mechanism mounted thereon as being set for exponent writing.

Figure 3 is a similar view with the part-spacing mechanism shown in position for subscript writing.

Figure 4 is a perspective view substantially taken from Figure 2, and shows the part-spacing mechanism as being set for normal writing, with parts broken away for clearness.

Figure 5 is a part-sectional front elevation of the left-hand side of a platen and platen-frame carrying novel part-spacing mechanism.

The left-hand side 10 of an Underwood 80 platen-frame, see Figures 1 and 5, is shown to carry journaled therein a shaft 11 of a platen 12 (partly shown), hubs 12^a being shown upon the shaft to locate the platen within the platen-frame. Step-by-step rotation or line-space movement of the platen with the aid of the usual feed-rolls 13 will feed a work-sheet 14 across the typing line at the front of the platen, where a type-bar 14^a is to indicate the printing. Ordinary line-spaces are determined by the usual ratchet-wheel 15, which is normally mounted to rotate with the platen-shaft in combination with a preferred detent-roller 16 which is resiliently held upon the platen-frame to engage in consecutive notches in said ratchet-wheel. Usual letter-feed and platen-return movement is not indicated on the drawing, except for the platen-return handle 17 (fractionally shown), which, mounted upon the platen, 95

55

100

frame in a well-known Underwood manner, also governs a pawl 18, which controls the line-space movement of the ratchet-wheel.

There is furthermore diagrammatically shown (see Figure 4) a clutch 19, generally found in an Underwood machine, which serves to connect or disconnect said ratchet-wheel 15 from the shaft 11, so as to cast off the line-space mechanism, to permit free platen rotation when so desired. An axially operating thumb-piece 19^a is fast upon the outer ends of two rods 20 to operate the clutch, the rods being shown to penetrate a usual finger-wheel 21, which forms the left-hand terminal of the platen-shaft.

Novel means is provided to bodily shift the detent, so as to rotate the platen fractions of a line-space in each direction from normal writing position. To form a support for the shiftable detent, there is provided a detachable vertical shield-plate 22, which has a horizontal top flange 23, by means of which it is screwed at 24 upon the usual top flange 25 of the side 10 of the platen-frame, so as to form a housing partly covering the line-space mechanism. The shield-plate upon its inner face carries the controllable detent which includes said detent-roller 16 journaled in the lower forked end of a curved 30 detent-arm 26. The upper end of said arm has pivotal connection at 27 with the horizontal arm of a bell-crank-lever 28. A vertical rising arm of said bell-crank-lever terminates in a finger-piece or handle 29, and has pivoted upon its outer face a cam-roller 30, for purposes hereinafter to be described.

The bell-crank-lever 28 is of flat material and extends through a slot or perforation 31 in the top flange 23 of the shield-plate 22, whereby a cutout 31^a accommodates the passage of the handle 29 through said slot when the device is being assembled. The detent-arm 26 is normally tensioned against the ratchet-wheel by means of a torsion spring 32 coiled around a stud or pin 33, which has a reduced end 34 (see Figure 5) by which to be riveted upon the side 10 of the platen-frame. The stud 33 may be the one which heretofore has served as a stationary pivot for the detent-arm in the Underwood machines. One end of said spring 32 may rest against a pin 34^a fast upon the side 10 of the platen-frame, and is accessible through an opening 35 in the shield-plate, the other end being allowed to engage in the circular groove 35^a of a roller 36, which is pivoted at 37 upon the outer face of the detent-arm 26. Adjustable stop-plates 38 are provided upon the top flange 23 to accurately limit the throw of the bell-crank-lever 28, i. e., the amount of fractional line-spacing in either direction, each plate having a slot 39 through which extends a screw 40 threaded into said top flange 23 of the shield-plate. It will be noted that each stop-plate has a slightly dropping edge

38^a (see Figure 4) which assists in locating the stop-plate upon said shield-plate.

Means to retain the bell-crank-lever in normal or in either of the part-spacing positions, includes a leaf-spring or spring-contact 41, which at one end is fastened by means of a through-bolt 42 and nut 43 upon the shield-plate 22, the other end of said contact having a stamped-out projection or catch 44, which engages in a hole or recess 45 provided upon the bell-crank-lever to hold the same in neutral, that is to say, in normal writing position. By throwing the bell-crank-handle or finger-piece 29 to the left for subscript (see Figure 2), the spring-contact 41 is urged out of neutral and to engage upon an adjacent right-hand beveled cam-face 46 of said bell-crank-lever, which in turn causes the lever to firmly rest against the stop-plate 38. When operating for subscript writing (see Figure 3), the catch will correspondingly engage upon a left-hand bevelled cam-face 47 of the bell-crank-lever.

To positively and conveniently restore the bell-crank to neutral, a cam-lever 48 is provided, which may be pivotally mounted at the outer face of the shield-plate 22 and find its bearing upon a shoulder of the above-mentioned through-bolt 42. The cam-lever 48 is formed with a finger-piece 48^a and operates in a plane parallel to the bell-crank-lever and adjacent thereto. The lever is formed with a substantially triangular loop 49 within which plays the above-mentioned cam-roller 30, which is provided upon the vertical arm of the bell-crank-lever and between the bell-crank-handle 29 and the top flange 23 of the shield-plate 22. That part of the inside edge of said loop that has the shape of an inverted V offers a compound cam-face 50 to co-operate with said cam-roller 30 to return the same from Figure 2 or Figure 3 part-spacing position back to neutral. The cam-lever is normally held in an upper inoperative position by a tension-spring 51 provided between a pin 52, fast upon a tail-extension 53 of said cam-lever 48, and another pin 54 provided upon the outer face of the shield-plate, so that the cam-roller 30 at its extreme shift positions rests against the lower inner corners of the loop 49 where the base edge 54^a joins the cam-faces 50 of loop 49, when the stop-plates 38 are set for the extreme travel of lever 28. A quick depression upon the finger-piece 48^a of the cam-lever (indicated in dot and dash in Figure 1) may urge the cam-roller 30 into the apex of the V-shaped cam-face 50, thus enabling the operator, after a subscript or superscript is written, to conveniently return the platen from Figure 2 or Figure 3 position back to normal writing position without requiring any careful attention in locating and setting the relatively small crank-lever. Subscripts and superscripts

130

which may be obtained are shown upon the work-sheet 14 in Figure 5.

The device eliminates a source of trouble liable to be encountered with accidental faulty positioning of the platen. The mounting of the device, including said detachable shield-plate 22 and said adjustable stops 38 thereon, offers ample opportunity for correct adjustment upon the machine. The whole structure of the device is such as to facilitate its being adapted to line-space wheels of various size and character. The provision of a clutch-mechanism to disconnect the line-space wheel renders the novel attachment independent of conventional line-space detent-release devices.

Variations may be resorted to within the scope of the invention, and portions of the improvements may be used without others.

Having thus described my invention, I claim:

1. In a typewriting machine, the combination with a rotatable platen and mechanism engaged therewith for line-spacing, of fractional spacing means for rotating said platen less than a full-line distance in either direction, and a manually-operated device separate from said means to directly engage said means and restore the same to its normal position.

2. In a typewriting machine, the combination with a rotatable platen and mechanism engaged therewith for line-spacing, of fractional spacing means for rotating said platen less than a full-line distance in either direction, and a manually-operated device separate from said means to restore the same by a single movement to its normal position.

3. In a typewriting machine, the combination with a rotatable platen and mechanism engaged therewith for line-spacing, of fractional spacing means including a member for rotating said platen less than a full-line distance in either direction, and a normally-operated lever having formed therein a V-notch for directly engaging said member to restore the same to its normal position by a single movement in one direction.

4. In a typewriting machine, the combination with a platen and a line-space wheel connected thereto, of a detent co-operative with said line-space wheel for normal line-spacing of the platen, a lever movable in opposite directions from normal position and controlling said detent so as to move the same together with the line-space wheel to rotate the platen fractions of a line-space in opposite directions from the typing line, adjustable means to limit the throw of the lever to less than a line-space in either direction, and means to hold said lever in normal position and in part-spacing position urged against said adjustable means.

5. In a typewriting machine, the combination with a platen and a line-space wheel

connected thereto, of a detent co-operative with said line-space wheel for normal line-spacing of the platen, a lever movable in opposite directions from normal position and controlling said detent so as to move the same together with the line-space wheel to rotate the platen fractions of a line-space in opposite directions from the typing line, adjustable stops to limit the throw of the lever to less than a line-space in either direction, and means to retain the lever in either normal central or part-spacing position, said means including a resilient detent-member which engages in a recess upon said lever when the latter is in normal position, or engages upon bevelled cam-faces provided upon said lever at either side of said recess, so as to hold said lever set against said adjustable stops.

6. In a typewriting machine, the combination of a platen, a line-space wheel connected thereto, means to rotate the platen and the line-space wheel a predetermined distance less than a line-space in either direction from normal position, means to retain the platen and the line-space wheel either in normal or in part-spacing position, and auxiliary means manually operated for positively restoring the platen and the line-space wheel from part-spacing position to normal.

7. In a typewriting machine, the combination with a platen, of a toothed line-space wheel connected to the platen, a finger-piece movable in one plane only and in opposite directions from normal position, means operated by the movement of said finger-piece to rotate the platen and the line-space wheel predetermined fractions of a line-space in opposite directions from the normal typing line, said finger-piece settable to remain in normal central and for part-spacing position of the platen, and independent auxiliary means manually operated for positively restoring the finger-piece from part-spacing position to normal.

8. In a typewriting machine, the combination with a platen, of a toothed line-space wheel connected to the platen, a finger-piece movable in one plane only and in opposite directions from normal position, means operated by the movement of said finger-piece, to rotate the platen and the line-space wheel in opposite directions from the normal typing line, said finger-piece settable to remain in normal central and part-spacing positions, adjustable means to determine part-spacing movement of said finger-piece, and independent auxiliary means manually operated for positively restoring the finger-piece from part-spacing position to normal.

9. In a typewriting machine, the combination with a platen, of a toothed line-space wheel connected thereto, an operating lever pivoted eccentrically of the platen and movable about its pivot in opposite directions from normal position, means operated by the

- movement of said operating lever to rotate the platen and the line-space wheel a predetermined distance less than a line-space in opposite directions from the normal typing line, said lever settable to remain in normal central and part-spacing positions, and a manually-operated pivoted cam-member operable to engage upon the lever to positively restore the same from part-spacing to normal.
10. In a typewriting machine, the combination with a platen, of a toothed line-space wheel connected thereto, an operating lever pivoted eccentrically of the platen and movable about its pivot in opposite directions from normal position, means operated by the movement of said operating lever to rotate the platen and the line-space wheel a predetermined distance, less than a single line-space, in opposite directions from the normal typing line, said lever settable for normal central or for part-spacing positions, a 70

operating lever to normal from either of its part-spacing positions.

16. In a typewriting machine, the combination with a rotatable platen and mechanism engaged therewith for line-spacing, of fractional spacing means for rotating said platen less than a full-line distance in either direction, adjustable stop-plates to limit the amount of said rotation, and a manually-operated device separate from said means to directly engage the same and restore it to the normal position.

17. In a typewriting machine, the combination with a rotatable platen and mechanism engaged therewith for line-spacing, of a fractional spacing lever for rotating said platen less than a full-line distance in either direction, said lever having a pair of inclined surfaces thereon, a resilient detent effective to engage either of said surfaces to urge the lever into one or the other of its extreme positions, and a manually-operated device separate from said lever to restore the same to its normal position.

25 18. In a typewriting machine, the combination with a platen mounted in a platen-frame and a toothed line-space wheel connected thereto, of a mounting to be fastened upon the platen-frame, an operating lever pivoted upon said mounting and which has pivotal connection with a spring-pressed detent-member which resiliently bears upon the teeth of said line-space wheel, so as to determine normal line-spaces when the operating 30 lever is held in normal position, said operating lever shiftable and settable to positions opposite from normal position, so as to move the detent-member together with the line-space wheel, to position the platen for writing above or below the normal typing line a 35 distance less than a normal line-space, and stop-plates adjustably fastened upon said mounting to determine the throw of the operating lever in either direction from normal 40 position.

45 19. In a typewriting machine, the combination with a platen mounted in a platen-frame and a toothed line-space wheel connected thereto, of a mounting to be fastened 50 upon the platen-frame, an operating lever pivoted upon said mounting, a spring-held detent-member having pivotal connection with said operating lever and which bears upon the teeth of said line-space wheel, so 55 as to determine normal line-spaces when the operating lever is held in normal position, said operating lever shiftable and settable to predetermined positions opposite from normal position, so as to move the detent-member together with the line-space wheel, to position the platen for writing above or below the normal typing line a distance less than 60 a line-space, means provided upon said mounting to retain said operating lever in normal or part-spacing position, and a hand- 65

operated cam-lever pivoted upon said mounting and operative to positively restore the operating lever from part-spacing position to normal.

CARL E. NORIN.
